DOUBLE-HINGED DOOR

William J. Van Meter, Macon, Mo.

Application June 25, 1949, Serial No. 101,437

11 Claims. (Cl. 16—147)

This invention relates to doors and other closures and to means for hingedly supporting the closures and to locking means and more particularly to mechanisms whereby a door may be opened from either side, though it is noted that in some of the claims the invention is not limited to doors that open on either side.

This invention is particularly suitable for refrigerators, cabinets and other articles of furniture for which the most convenient location in a room may be against a wall which may make it inconvenient to have the door open at the side next to the wall. Circumstances may require that the furniture be moved to another location requiring the door to be opened from the other side. An object of the invention is to provide furniture suitable for all such locations.

Also this invention is suitable for doors of buildings where arrangement of furniture or other conditions may require that the door be opened at one side or the other.

Another object of the invention is to provide an improved arrangement of this kind wherein the hinge pin operates both as a locking bolt and a hinge pin.

The invention relates to novel improvements in door hinging and bolting or latching means and has for another object to provide an improved construction of this character which will be highly efficient in use and economical in manufacture.

Other objects of the invention are to provide a simple combination and arrangement of parts in the hinge structures of a door which will facilitate and make very easy the opening, closing or bolting of the door at either side of the door.

A further object of the invention is the provision of a simple control mechanism for holding the hinge bolt operating means in a bolting hinging position to prevent the door from being opened at the bolted side when it is open at the other side.

A further object of the invention is to provide a latch bolt arrangement which will not cause resistance to the closing and opening of the door.

Additional objects of the invention are to effect simplicity and efficiency in such locking mechanism and to provide an extremely simple mechanism of this kind which is easy, durable, and reliable in operation, and economical to manufacture and install.

Still other objects of the invention will appear as the description proceeds; and while herein details of the invention are described in the specification and some of the claims, the invention as described in the broader claims is not limited to these, and many and various changes may be made without departing from the scope of the invention as claimed in the broader claims.

The inventive features for the accomplishment of these and other objects are shown herein in connection with a door mounting and latching mechanism which briefly stated is shown in combination with a door having at each side a pair of aligned bolts slidably biased into corner openings of the door frame. A handle adjacent to and operatively connected with each pair of aligned bolts serves for withdrawing the bolts. A rearwardly biased latch

2

member at each side of the door has a projection engageable with the frame when the door is closed and biased to engage and hold the detent lugs of the adjacent bolts when the bolts are withdrawn and the adjacent side of the door is opened. A bar guided across the door is at each end engageable with adjacent bolts to hold the bolts against withdrawal; and an operative connection between each handle and the bar insures that operation of the handle will cause the adjacent end of the bar to clear the adjacent bolts and move to hold the other bolts against withdrawal. Each latch member when the adjacent side of the door is opened is biased to hold the bar against movement away from the bolts at the other side of the door.

15 In the accompanying drawing showing, by way of example, one of many possible embodiments of the invention,

Fig. 1 is a fragmental front elevation partly in vertical section showing the bolt control mechanism;

20 Fig. 2 is a fragmental horizontal sectional view, partly in plan, the section being taken substantially on the line 2—2 of Fig. 1, looking in the direction of the arrows of said line;

Fig. 3 is a fragmental vertical sectional view, partly 25 in elevation, the section being taken substantially on the line 3—3 of Fig. 2, looking in the direction of the arrows of said line; and

Fig. 4 is a fragmental side elevation drawn on a larger 30 scale, partly in section substantially on the line 4—4 of Fig. 2, looking in the direction of the arrows of said line.

My improved double hinged door is shown in combination with a door frame 6 having upper and lower frame members 7, 8, rearwardly converged side faces 9 and frontwardly facing narrow stop faces 10 at the rear edges 35 of said side faces. The upper and lower frame members have near their ends axially vertically aligned inwardly tapering hinge pin socket openings 11.

The door is shown as substantially hollow and having 40 parallel front and rear walls 12, 13 and rearwardly converging side walls 15 fittingly engageable with said converging faces 9, the rear wall 13 being a removable panel. Blocks or bars 16 have parts in the four corners of the door provided with guide bores 17 aligned with said openings in which bores are slidably locking hinge bolts 18 45 provided with tapering end parts rotatably fitting in said openings 11. Shanks 19 of angular cross-section fast on and aligned with said bolts and extending a distance in the interior of the door are provided at the free end and intermediate parts respectively with detent and actuation lugs 20, 21 projecting toward the opposite side of the door.

Said bolts, shanks and lugs are duplicated at opposite sides of the door, as are also all operative parts associated therewith.

55 Guide bracket plates 23 fast on adjacent walls of the door transverse to the shanks are provided with angular openings fittingly slidably non-rotatively receiving the shanks 19. A helical locking spring 24 on each shank compressed between the guide bracket plate 23 and a

60 collar 25 fast on each shank serves for yieldably moving the bolts into the socket openings 11. Upper and lower bearing brackets 27 adjacent to each aligned pair of shanks 19 are mounted on the inner face of the front wall and are provided with vertically axially aligned bearing openings near said actuation lugs 21 carrying an actuating

65 shaft 28 having reduced bearing ends 29 in said bearing openings. Helical cams 30 on said shaft are normally disposed near the front wall 12 with a rear corner 31 (Fig. 3) of the cam engaged with the face of the actuation lug 21 nearest the bolt. The outer corner 32 of the cam nearest the front wall is more distant from the bolt, a distance equal to the travel of the bolt. A handle member 33 fast on said shaft has a radial portion 34

70

extending through an opening 35 (Fig. 2) in the front wall, and a handle portion 36 on the free end of the radial portion normally extending substantially parallel with the front wall and pointing toward the opposite side of the door.

A spring 37 mounted on the front wall of the door and pressing on a finger 37' carried on the shaft 28 urges the handle to a position to allow the bolts to engage in the socket opening.

When the handle portion of either handle member is pulled frontwardly, the cams 30 cam the actuation lugs 21 of the adjacent shanks 19 inwardly and withdraw the bolts 18 from the socket openings 11 and allow the adjacent side of the door to open, and allow the door to hinge on the undrawn bolts on the opposite side of the door.

The rear wall of the door has a horizontally elongated opening 39 adjacent to the adjacent stop face 10, the axis of the hole passing through the hole being axially aligned with a point between the adjacent detent lugs 20. A latch member 40 comprising a hollow cylindrical body 41 open at the front end and closed at its rear end has a reduced rear end portion 42 of elongated cross section slidably and non-rotatively fitting in said elongated opening 39. Upper and lower radial extensions 43 on the front end of the body extending in a plane frontward and spaced from the adjacent detent lugs 20, are each provided with a rearwardly projecting latch lug 44 projecting in rearward or door closing direction adjacent to the adjacent detent lug 20. A guide rod 45 mounted fast on the front wall aligned with and slidably received in the hollow body 41 has a transverse inner end face engaged by a helical latch spring 46 in said body compressed between said transverse face and closed inner end of the body. When the hinge bolts 18 are withdrawn, moving the detent lugs to an inner position 20a, and when the adjacent side of the door is opened, said latch spring 46 moves the latch member to move the latch lugs 44 adjacent to the outer face of the detent lugs 20 to hold them and the bolts in withdrawn position until the door is again closed, causing engagement of the reduced end 42 of the latch member with said stop face 10 to push back the latch member and release the detent lugs 20 from the latch lugs 44 and allow the locking spring 24 to drive the bolts 18 into socket openings 11.

Transversely aligned guide brackets 45' mounted on opposite sides of the mid-part of the outer wall 12 and having angular guide openings slidably receive a control bar 47 of angular cross-section extending across the door in the plane of said shanks 19, said bar being engaged and frictionally held in any position to which it may be moved by a friction spring 47' mounted on a bracket 45'. The bar 47 is bifurcated at each end to provide a pair of tapered detent ends 48 engageable over the inner faces of the detent lugs 20, at one side of the door only at a time, to hold the bolts 18 from being withdrawn from the socket openings. The length of the control bar is such that the detent lugs at one side only of the door may be cleared at the same time. A rearwardly disposed bracket 49 on the control bar has a laterally disposed engagement part 50 engageable with a rearwardly disposed radial control finger 51 on each handle shaft 28 on the side of the finger remote from the adjacent shanks, whereby when the handle is pulled, the bar is moved or held to cause the adjacent detent ends 48 to clear the adjacent detent lugs 20 to allow the adjacent bolts to be withdrawn; while the detent ends 48 at the other end of the bar are moved or held to engage over the detent lugs at said other end to prevent the withdrawal of the bolts at the side adjacent to such ends.

Each end of the control bar 47 has an end face 54 between the detent ends 48. The latch member body 41 is provided at its outer end with an inwardly facing abutment piece or lug 55. When a handle is pulled, the finger 51 causes the adjacent end face 54 to move in a plane

parallel to the length of said piece 55 until the face 54 and the inner free end of said piece are in approximately the same plane and the face 54 clears the end of said piece 55, and then when the door is opened said piece 55 moves rearwardly to face said end face 54 to prevent the bar 47 from moving toward such piece 55, thus preventing the detent ends 48 at the other end of the bar 47 from being removed from the detent lugs 20.

The operation of the invention will be obvious from the foregoing. The door being closed, if the left side of the door as in Fig. 1 is to be opened, the handle 36 at that side is pulled, causing the bar 47 to be held or moved to the right so that the detent ends 48 clear the adjacent bolts before the cams 30 retract the adjacent bolts 18. At the same time the detent ends 48 at the right of the door hold the bolts at the right against withdrawal, and the bar 47 is disposed behind the lug 55 at the right to hold it and consequently the rear end portion 42 against rearward movement when the door opens. The engagement of the inclined or cam face of the detent end 48 with the inclined or cam face of the detent lug 20 assures maximum engagement of the associated bolt 18 in its socket opening 11.

After the bolts 18 at the left are thus withdrawn, continued pull on the left handle 36 opens the door, and allows the latch member 40 at the left to be moved rearwardly by the spring 46, causing the latch lugs 44 to engage the side of the detent lugs 20 nearest the bolts, thus to hold the bolts retracted in the position 20a. When this takes place the abutment piece 55 of the latch member 40 is moved rearwardly and placed opposite to the left end face 54 of the bar 47 to hold the bar against leftward movement away from the ends of the shanks 19 at the right of the door, thus to prevent the withdrawal of the bolts at the right. When the handle is released the spring 37 engaging the finger 37' restores the handle to the position of the full lines of Fig. 2.

Manipulation of the handle 36 is not necessary when the door is reclosed, as the door may be merely pushed closed. When the door is reclosed, the reduced rear end portion 42 engages the stop face 10 causing the latch member 40 to be restored to the position of the solid lines of Fig. 4, thus releasing the detent lugs 20, allowing the bolts 18, to be projected into the sockets 11 and disposing the piece 55 away from the face 54.

The operation of opening the door at the right side of the door is effected by pulling on the handle at the right side of the door and is substantially the same as for the left side as will be readily understood.

I claim as my invention:

1. In combination, a door having at each side a pair of yieldably projected bolts each having a detent shoulder; a movable handle adjacent to and operatively connected with each of said pairs for withdrawing the bolts; a latch member within the door adjacent to each of said pairs and biased to project from the door and adapted when the bolts are withdrawn to move to a holding position to engage and hold the detent shoulders; a movable assembly having parts engageable with the bolts at one side at a time to hold the bolts against withdrawal; a connection between each handle and said assembly adapted when a handle is operated to move the assembly to cause said parts to clear the adjacent bolts and move to hold the other bolts against withdrawal; each latch member being formed to engage and hold the adjacent part of the assembly against movement to a holding position to hold the adjacent bolts and to hold the other parts of the assembly against movement to clear the opposite bolts, when the latch member is moved to said holding position.

2. In combination, a door adapted to be disposed in a door frame having corner socket openings at both sides; pairs of aligned bolts slidably mounted in the door and positioned to be biased into said openings and provided with detent lugs; a handle adjacent to and operatively connected with each pair of aligned bolts for withdrawing

the bolts; a latch member biased in door closing direction at each side of the door engageable with the frame and biased to engage and hold the adjacent detent lugs when the bolts are withdrawn and the adjacent side of the door is opened; a bar longitudinally slidably guided across the door and at each end engageable with adjacent bolts to hold the bolts against withdrawal; an operative connection between each handle and the bar to cause operation of the handle to move to cause the adjacent end of the bar to clear the adjacent bolts and move to hold the other bolts against withdrawal; each latch member when the adjacent side of the door is opened being biased to engage and hold the bar against movement toward such latch member.

3. In combination, a hollow door having a front wall; pairs of alined bolts at the respective side edges of the door slidably biased from the door and provided with lateral lugs and detent shoulders; an actuating shaft rotatably mounted in the door adjacent and parallel to each pair of alined bolts; helical cams on each shaft engageable with the face of adjacent lug nearest the bolt; a handle on each shaft extending parallel to and frontwardly of the front door wall, and means engageable with the shoulders for holding the bolts retracted.

4. In combination, a door; pairs of alined bolts mounted in the door and slidably biased to project from the door; a handle adjacent to and operatively connected with each pair of alined bolts for withdrawing the bolts; a latch member biased in door closing direction at each side of the door; a bar guided across the door and at each end portion having detent ends engageable with adjacent bolts to hold the bolts against withdrawal; an operative connection between each handle and the bar to move the bar to clear the adjacent bolts and move to engage and hold the other detent ends to a position to hold the bolts against withdrawal; said bar having end faces between the detent ends; each latch member being provided with an abutment lug having an abrupt end face facing toward the control bar, and adapted to face said end face of the control bar when the latch member is moved in door closing direction, to prevent the detent ends at the other end of the bar from being removed from adjacent bolts.

5. A door having at each side a pair of alined oppositely yieldably projected bolts; means adjacent to and operatively connected with each of said pairs for withdrawing the bolts; a biased one-piece latch member adjacent to each of said pairs and adapted when the bolts are withdrawn to be urged to engage and hold the adjacent bolts withdrawn; a single bar guided across the door and engageable with the bolts at one side at a time to hold the bolts against withdrawal; each of said means being constructed and adapted when such means is operated to withdraw the adjacent bolts and to move to cause the bar to move to clear the adjacent bolts and hold the other bolts against withdrawal; each latch member being constructed to engage and hold the bar against movement toward such latch member and from the opposite bolts when the latch member is moved to engage the adjacent bolts.

6. In an assembly for movable mounting and holding a door in a frame, the combination of a pair of alined oppositely yieldably projected bolts at each side of the door, each having an actuation shoulder; a handle pivoted adjacent to each of said pairs; parts operatively connected with each handle for engaging adjacent actuation shoulders for withdrawing the bolts; means to hold the withdrawn bolts withdrawn when the adjacent side of the door is open and to release the bolts when the door is closed; a bar guided across the door and engageable with the bolts at one side at a time to hold the bolts against withdrawal and having an actuating shoulder adjacent to each handle; a part connected to each handle and adapted when a handle is operated to push upon the shoulder of the bar to cause the bar to clear the adjacent bolts and hold the other bolts against withdrawal; yieldable means

adjacent to each handle, operative each time said handle is operated to automatically restore the handle to normal regardless of the position of the door, bar and bolts, and to cause said parts to disengage the actuating shoulders when the bars and bolts have been actuated; whereby after the handle is automatically restored, the door may be closed and the bolts released without any movement of the handle relative to the door.

7. In an assembly for movably mounting a door in a door frame, the combination of a pair of alined oppositely yieldably projected bolts at each side of the door; a single bar slidably disposed transversely across the door and positioned and constructed to be moved to engage both bolts at one side only at a time to hold the bolts against withdrawal; and a one-piece latch member slidably mounted adjacent to each pair of bolts and biased to engage the door frame and be held in an inner position when the door is closed and biased to move to a projected position when the door is open; each latch member being positioned and constructed when in projected position to engage and hold the bar against movement toward such latch member and against movement from holding the opposite bolts.

8. In an assembly for movably mounting a door in a door frame, the combination of a pair of alined oppositely yieldably projected bolts at each side of the door; a single bar slidably disposed across the door and positioned and constructed to be moved to engage both bolts at one side only at a time to hold the bolts against withdrawal; operating means mounted on the door adjacent to each pair of bolts operatively engaged with each adjacent bolt to withdraw the bolts, and carrying a part operatively engaged with the bar to withdraw the bar from said adjacent bolts and to move the bar to engage and hold withdrawal of the other pair of bolts; and a latch member slidably mounted adjacent to each pair of bolts and biased to engage the door frame and be held in an inner position out of engagement with said bolts when the door is closed and biased to move to a projected position when the door is open; each latch member being positioned, constructed and adapted when in projected position and the bolts have been withdrawn, to engage the adjacent bolts and hold the bolts withdrawn, and to engage and hold the bar against movement toward such latch member and the adjacent bolts.

9. In an assembly for fastening a door, the combination of pairs of alined bolts at the respective side edges of the door slidably biased to project an end from the door and each provided with a lateral lug, an actuating shaft rotatably mounted in the door adjacent and parallel to each pair of alined bolts; helical cams on each shaft each engageable with the face of the adjacent lug of the nearest bolt; a handle on each shaft extending substantially horizontally parallel and frontwardly of the door.

10. In an assembly for movably mounting a door in a door frame, the combination of a pair of alined oppositely yieldably projected bolts at each side of the door; a single bar longitudinally slidably disposed transversely across the door and positioned and constructed to be moved to directly engage both bolts at one side only at a time to hold the bolts against withdrawal; operating means adjacent to each pair of bolts operatively engaged with each adjacent bolt to withdraw the bolts, and operatively connected with the bar to withdraw the bar from said adjacent bolts before withdrawal of the bolts and to move the bar to engage and hold against withdrawal the other pair of bolts; and a latch member slidably mounted adjacent to each pair of bolts and biased to engage the door frame and be held in an inner position when the door is closed and biased to move to a projected position when the door is open; each latch member having rigid thereon an abutment piece positioned and constructed when the latch member is in inner position to clear said bar, and when the latch member

is in projected position to engage the adjacent end of the bar and hold the bar against movement from engagement with the opposite bolts.

11. In an assembly for movably mounting a door having a rear opening in a door frame having corner sockets, the combination of a pair of aligned oppositely yieldably projected bolts at each side of the door engageable in said sockets and each provided with a lateral detent lug; a handle adjacent to and operatively connected with each of said pairs for retracting the bolts; a single bar longitudinally slidably disposed across the door and positioned and constructed to be moved to engage both bolts at one side only at a time to hold the bolts against withdrawal; handle operated operating means adjacent to each pair of bolts operatively engaged with each adjacent pair of bolts to withdraw the bolts, and operatively connected with the bar to withdraw the bar from said adjacent bolts before withdrawal of the bolts and to move the bar to engage and hold against withdrawal of the other pair of bolts; a latch member at each of said sides adjacent to said lugs and comprising a rear end portion slidably fitting in said opening, and engageable with the frame when the door is closed; spring means for yieldably pressing the latch member rearwardly against the door frame when the door is closed and to a projected position when the door is open; each member having upper and lower extension frontward and spaced from the adjacent detent lugs and provided with rearwardly projecting latch

5
10
